(57) **CLAIM**

The ornamental design for a juice extractor, as shown and described.

DESCRIPTION

FIG. 1 is a front, top and right side perspective view of a juice extractor showing the new design.

FIG. 2 is a right side view thereof.

FIG. 3 is a left side view thereof.

FIG. 4 is a front view thereof.

FIG. 5 is rear view thereof.

FIG. 6 is a top view thereof; and,

FIG. 7 is a bottom view thereof.

In the drawings, the broken lines in FIG. 7 depict portions of a bottom end that form no part of the claimed design.
